2 SHEETS—SHEET 2.

UNITED STATES PATENT OFFICE.

WILLIAM JOHN STAFFORD, OF QUINCY, ILLINOIS.

STOVE.

1,192,701.

Specification of Letters Patent. Patented July 25, 1916.

Application filed April 27, 1916. Serial No. 94,016.

To all whom it may concern:

Be it known that I, WILLIAM J. STAFFORD, a citizen of the United States, residing at Quincy, in the county of Adams and State 5 of Illinois, have invented certain new and useful Improvements in Stoves; and I do declare the following to be a full, clear, and exact description of the invention, such as will enable others skilled in the art to which 10 it appertains to make and use the same.

My invention relates to improvements in stoves of the class designed for cooking purposes and for burning solid, liquid or gaseous fuels, the present application being generic in part to the structure herein described and to that disclosed in my copending U. S. application, Serial No. 93213, filed April 24, 1916.

One object of the invention is to locate 20 the oven burner at a point at which it will be readily accessible for cleaning and repairing, and to provide a shield plate for covering said burner when solid fuel is being used, thereby preventing the accumulation of soot 25 and the like on said burner.

Another object is to so position the aforesaid shield plate as to cause it to equalize the draft of hot air through portions of a flue which are of unequal cross sectional 30 area.

Yet another object is to provide a system of dampers connected for simultaneous movement with the shield plate in order that by a single operation said plate and dampers 35 may be properly positioned for burning solid fuel or may be correctly disposed for consuming gaseous or liquid fuel.

A still further object is to provide an improved flue leading from the burner and 40 having a lateral extension overlying the top of the oven to carry heat around said oven and to so position one of the aforesaid dampers as to allow it to lie flat upon said extension when open, thereby protecting the 45 latter against the intense heat from the firebox when solid fuel is being consumed.

With the foregoing general objects in view, the invention resides in certain novel features of construction and in unique combinations of parts to be hereinafter fully described and claimed, the descriptive matter 50 being supplemented by the accompanying drawings which constitute a part of this application and in which:

Figure 1 is a rear elevation of the improved stove; Fig. 2 is a central longitudinal

sectional view thereof; Fig. 3 is a horizontal sectional view taken on the planes of the line 3—3 of Fig. 2; Fig. 4 is an end elevation with parts broken away and in section; 60 and Fig. 5 is a perspective view of the dampers and the operating means therefor.

In specifically describing the construction shown in the drawings above briefly described, similar characters will be placed on 65 corresponding parts throughout the several views, and reference will be herein made to the numerous elements by their respective indices. To this end, the numeral 1 designates an appropriate base preferably having 70 legs 2, said base supporting thereon a shell 3 whose top 4 is provided at one end with a grating 5 and at other points with openings closed normally by lids 6. Gas burners 7 are disposed beneath the grating 5 and 75 housed within a suitable compartment 8, a portion of which projects from one end of the shell 3. At its opposite end the shell is equipped with a fire-box 9 and an ash pit 10 beneath the same.

An oven 11 is spaced from the top, bottom and ends of the shell 3, said oven being separated from the fire-box and ash pit by an upright partition 12 which is spaced from the oven and extends laterally at 13 80 along a portion of the top thereof, the space 14 between the oven and partition constituting a contracted portion of a flue F which extends beneath the oven as shown at 15 and upwardly along the other end of said 85 oven as depicted at 16, the portions 14 and 16 both communicating with the space 17 between the oven and the top 4 of the stove.

An L-shaped partition 18 extends downwardly between the outer end of the oven 95 and the adjacent end of the shell 3 and continues horizontally between the bottoms of said oven and shell, the horizontally extending portion of said partition preferably terminating midway the ends of the oven as 100 shown in Fig. 2. A second partition 19 extends between the tops of the oven and shell, one end of said partition terminating at the inner wall of the compartment 8 and thus leaving an opening 20 between itself and 105 the upper end of the partition 18. The other end of said partition 19, however, joins a vertical wall 21 which extends rearwardly therefrom to the rear side of the shell 3, said wall serving to prevent the entrance 110 of smoke and the like from the fire-box into the space behind the partition 19 with-

out first traveling in front of said partition and through the opening 20.

5 A damper 22 is pivoted adjacent its lower edge and is adapted to either obstruct or allow communication between the space 17 and the fire-box 9, said damper when open for allowing the box 9 to be used, lying flat upon the lateral extension 13 of the partition 12 and thus protecting the same 10 against the intense heat from the fire.

15 A damper 23 is pivotally mounted within the opening 20 and is provided with an operating rod 24 leading through the front of the stove. When this damper is open 15 with a fire burning in the box 9, the smoke and hot air from said fire may pass through the space 17 in advance of the partition 19, through the opening 20 and then through an outlet opening 25 into a hood or the like 26 from which an ordinary stove pipe extends. When, however, the damper 23 is closed, the heat from the fire-box must pass over the oven through the space 17, downwardly in advance of the partition 18, horizontally 25 around the end of this partition and then retrace its course in rear of said partition, whereupon it may be discharged through the opening 25, which latter is provided with a pivoted damper 27.

30 The end wall of the shell 3 remote from the fire-box and ash pit, which wall is designated by the numeral 28, has at its lower end an opening which extends throughout the width of said wall and terminates at 35 the bottom 29 of the shell, this opening being normally closed by a removable apertured plate 30 which is preferably concavo-convex in cross section with its convex face positioned outwardly. The plate 30 may be secured in place by any preferred means but the lower edge thereof preferably has formed thereon a number of depending fingers 31 which project into openings 32 in any suitable fixed part of the stove, said 40 openings being preferably in the upper edge of the base 1. This will effectively hold the plate in position as long as the upper edge thereof is prevented from tilting outwardly and for preventing such movement suitable 45 turn buttons or the like 32' are provided. It will be understood that regardless of the construction shown, the plate 30 may be secured in position in any suitable manner.

50 Mounted non-rotatably in the flue F adjacent the inner face of the plate 30 and extending substantially throughout the width of said flue is a burner 33 which is adapted in the present embodiment of the invention to burn natural or manufactured gas, although it might well be of such construction as to permit the burning of liquid fuel. The burner 33 passes through a notch 34 in the outer corner of the partition 18 and is provided on both sides of said partition with 55 diverging fuel discharge nozzles 35, said

nozzles being disposed in diverging relation in order that they may direct independent jets of flame of equal intensity in both portions 15 and 16 of the flue. Fuel is supplied to the burner 33 through a neck 70 36 which extends through a notch 37 in the lower edge of plate 30, the outer end of said neck being connected with a gas pipe 38. This arrangement will effectively hold the burner rigidly as long as the plate 30 is 75 in position but by removing said plate it will be obvious that the pipe 38 may be sufficiently sprung to remove the aforesaid burner for cleaning or repairing the same, if this should be necessary. Here again, it 80 is to be understood that although the burner 33 is shown and described as mounted in a certain specific manner, other ways may well be adopted if found desirable.

85 For the purpose of preventing soot and the like from accumulating on the burner 33 when the fire-box 9 is in operation, an arcuate shield plate 39 is pivotally mounted at one edge directly above said burner and in close proximity to the plate 30, said plate 90 being preferably formed as an integral part of a rock shaft 40 whose rear end projects beyond the shell 3 and whose front end is squared as shown at 41 for the reception of an appropriate tool, whereby it may be 95 rocked.

When the burner 33 is in use the shield plate 39 is raised as shown in Fig. 2 and will then extend obliquely into the vertical portion 16 of the flue, said plate serving to partially 100 close this portion of the flue, thus preventing the passage of heat therethrough with greater ease than through the contracted portion 14. This equalizes the travel of heat and prevents it from short circuiting through the 105 vertical portion 16. When a fire is burning in the box 9 the plate 39 will be swung downwardly across the corner of the flue in which it is located (see dotted lines in Fig. 2) and when in this position, it will effectively prevent the accumulation of dust and 110 soot upon the burner 33. The bottom 29 of the shell 3 is preferably formed with an integral upstanding rib 42 against which the free edge of plate 39 abuts when lowered. 115

The portion 15 of the flue may be readily cleaned out when the plate 39 is lowered, the plate 30 being provided with a clean out slot normally closed by a door 43, said slot being so positioned as to be disposed 120 at the upper edge of the plate 39 when the latter is in its lowermost position. By the use of an ordinary scraper all soot and the like which may have accumulated upon the bottom 29 of the shell may be drawn upwardly along the plate 39 and outwardly through the aforesaid slot. 125

If the burner 33 and its shield plate 39 be employed in stoves not equipped with partitions such as 18, said plate will be un- 130

interrupted throughout its length, but when such partition is used as is the case in the present embodiment of the invention, said plate will be formed with a transverse slot 544 which receives said partition as shown clearly in Fig. 4. The lower corner of the oven 11 adjacent to the ash pit 19 is provided with a rib 45 which extends toward said pit, said rib 10 co-operating with a damper 46 which is pivotally mounted in the lower end of the portion 14 of the flue, said damper being adapted to be closed when solid fuel is being consumed in the fire box 9. The damper 46 is 15 preferably mounted on a rock shaft 47 whose rear end projects beyond the rear side of the stove. The dampers 22 and 27 are also preferably mounted upon rock shafts 48 and 49 respectively, these shafts 20 likewise projecting beyond the rear side of the stove. This construction is provided in order that the shafts 47, 48 and 49 of the three dampers and the shaft 40 of the shield plate 39 may all be connected for simultaneous movement when said shaft 40 is turned by the application of a suitable tool to the squared portion 41 thereof, the connections between the parts in question being such as to properly position the numerous 30 dampers for burning solid fuel when the plate 39 is swung downwardly or for using the burner 33 when said plate is moved upwardly.

The connections above referred to might 35 well be in a number of forms but as simple and efficient means for accomplishing the required results, the construction shown is preferably used. Crank arms 50 and 51 project from the rear ends of the shafts 47 and 40 48 and are connected by a link 52 pivoted at its ends to said arms, the upper portion of said link being loosely connected by a shorter link 53 with a crank arm 54 which projects rearwardly from the rock shaft 49 45 of damper 27. The crank arm 50 is connected pivotally with one end of a horizontal link 55 whose other end is pivoted to a crank-arm 56 extending from the rear end of the shaft 40. By this construction when 50 the shaft 40 is rocked to lower the plate 39, the damper 46 will be closed while dampers 22 and 27 will be opened, thus placing the stove in condition for the burning of solid fuel. When, however, said shaft 40 is 55 rocked to raise the plate 39 as shown in full lines in Fig. 2, the damper 46 will be opened and dampers 22 and 27 will at the same time be closed. This places the stove in condition for using the burner 33.

60 A vent 57 is employed in connection with the parts above described, said vent establishing communication between the hood 26 and the space 17 and also between said hood and the compartment 8 to allow the escape 65 of poisonous gases from the stove.

From the foregoing, taken in connection with the accompanying drawings, it will be obvious that I have provided a convertible stove which possesses a number of unique features of construction, particular emphasis being laid upon the two-fold function of the shield plate 39, upon the means for operating the numerous dampers simultaneously with the operation of said plate 39, the lateral extension 13 of the partition 12 70 and the manner in which this extension is protected by the damper 22.

In conclusion, I will state that although I have shown and described certain specific details for accomplishing probably the best 80 results, numerous changes may be made within the scope of the invention as claimed without sacrificing the main advantages thereof.

I claim:

1. In a convertible stove, an oven, a flue extending beneath and along the ends of said oven, said flue having a contracted portion, a fire-box in dampered communication with said flue, a burner mounted non-rotatably in one angle of the flue and extending substantially throughout the width of said flue, and a shield plate pivotally mounted in the flue and adapted to swing over said burner when solid fuel is being consumed in the fire-box, said shield plate otherwise serving to partially close a part of the flue to prevent the discharge of heat through the larger portion thereof with greater ease than through the contracted portion.

2. In a convertible stove, an oven, a flue extending beneath and along the ends of said oven, a fire-box, a damper for controlling communication between said fire-box and flue, a burner mounted non-rotatably in said flue and extending substantially throughout the width of the latter, a pivotally mounted shield plate adapted to swing over said burner when the damper is open to permit consumption of solid fuel in the fire-box, and operating connections between said damper and shield plate for operating the two simultaneously.

3. In a convertible stove, an oven, a flue extending beneath and along the ends of said oven, said flue having a contracted portion, a fire-box, a damper for controlling communication between said fire-box and flue, a burner mounted non-rotatably in one angle of said flue and extending substantially throughout the width of the latter, a pivotally mounted shield plate adapted to swing over said burner when the damper is opened to permit consumption of solid fuel in the fire-box, said plate otherwise serving to partially close a part of the flue to prevent the discharge of heat through the larger portion thereof with greater ease than the contracted portion, and operating

connections between said damper and said shield plate for operating the two simultaneously.

4. In a convertible stove, an oven, a smoke and gas outlet, a flue extending beneath and along both ends of the oven, a damper controlling communication between said flue and said outlet, a fire-box, a second damper controlling communication between the same and the flue, a burner mounted non-rotatably in the flue, a shield plate mounted pivotally in the flue and adapted to swing over the burner when the aforesaid dampers are opened to allow consumption of solid fuel in the fire-box, and operating connections between said dampers and said shield plate for operating the three simultaneously.

5. In a convertible stove, an oven spaced downwardly from the top of the stove, a fire-box at one end thereof, a flue passing beneath the oven and along the ends thereof, the portion of said flue between the oven and fire-box being contracted and extending laterally along the top of the oven, a burner in said flue, a pivoted damper controlling communication between the fire-box and the space above the oven, and an outlet from said space, said damper when opened lying on the top wall of said laterally extending portion of the flue and protecting the same against the intense heat from the fire-box.

6. In a convertible stove, an oven, a fire-box adjacent one end thereof, a flue extending beneath the oven and along the ends thereof, the portion of said flue between the oven and fire-box being contracted, a burner in the angle of the flue remote from the fire-box and extending substantially throughout the width of said flue, and an arcuate shield plate pivoted at one edge above the burner and adapted to swing downwardly across said angle of the flue to protect the burner when solid fuel is being consumed in the fire-box, said plate otherwise extending obliquely into the part of the flue above the burner and partly closing the same to prevent the discharge of heat therethrough with greater ease than through the contracted portion of the flue.

7. In a convertible stove, an oven spaced downwardly from the top of the stove, a smoke and gas outlet from the space above said oven, a fire-box adjacent one end of said oven, a damper controlling communication between said fire-box and said space, a flue extending below and along both ends

of said oven, the ends of said flue communicating with said space and the portion of the flue between the oven and fire-box being contracted, a second damper for closing said contracted portion, this damper being open when the other is closed, a burner mounted in the angle of the flue remote from the fire-box and extending substantially throughout the width of said flue, a shield plate pivoted at one edge above the burner, said plate being adapted to swing downwardly across the aforesaid angle of the flue to protect the burner when solid fuel is being consumed, the first and second dampers being then respectively open and closed, said shield plate otherwise extending obliquely into the part of the flue above the burner to partly close the same and prevent the escape of heat therethrough with greater ease than through the contracted portion of the flue, and operating connections between the two dampers and the shield plate for moving them to their proper positions simultaneously.

8. In a convertible stove, a shell having at one end a fire-box, an oven in said shell and spaced downwardly from the top thereof, a flue extending beneath the oven and along both ends thereof, said flue communicating at its opposite ends with the space above the oven, the end wall of the shell remote from the fire-box having a horizontally elongated opening at its lower end, a burner inserted into the flue through said opening and extending substantially throughout the width of said flue, said burner having an outwardly projecting fuel supply neck between its ends, a removable plate normally closing the aforesaid opening and having in its lower edge a notch receiving said neck therein, and an arcuate shield plate pivoted at one edge above the burner and adapted to swing downwardly thereover to protect the same when solid fuel is being consumed in the fire-box, said plate otherwise extending obliquely into the part of the flue above the burner and partly closing the same to prevent heat from being too readily discharged therethrough.

In testimony whereof I have hereunto set my hand in presence of two subscribing witnesses.
